UNITED STATES PATENT OFFICE.

HARRY INGRAM, OF BROOKLYN, NEW YORK, ASSIGNOR OF ONE-HALF TO CHARLES P. FAY AND THADDEUS FIRTH, JR., OF SAME PLACE.

HAT-FASTENER.

SPECIFICATION forming part of Letters Patent No. 595,480, dated December 14, 1897.

Application filed September 4, 1897. Serial No. 650,585. (No model.)

To all whom it may concern:

Be it known that I, HARRY INGRAM, a resident of Brooklyn, Kings county, State of New York, have invented an Improved Hat-Fastener, of which the following is a specification.

My invention relates to devices for securing a hat or bonnet on the head of a wearer, and has for its object to produce an efficiently-operating device of the character described.

My invention will be understood by referring to the accompanying drawings, in which—

Figure 1 is a side elevation of a hat-fastener embodying my invention and showing also in dotted lines a hat or bonnet to which it is secured. Fig. 2 is a side elevation of one section of the hat-fastener. Fig. 3 is an underneath plan view of the hat-fastener, showing the same as collapsed. Fig. 4 is a plan view of the section shown in Fig. 2. Fig. 5 is a detail underneath view of a portion of the fastener, and Fig. 6 is a section on line 6 of Fig. 5.

The device illustrated consists of a pair of sections *a b*, which are slidably connected to each other, as by means of loops *c d*, so that the two sections may be slid on each other to collapse the fastener. Each section is provided with means, such as the perforated plates *e*, for securing the same to a hat or bonnet. Each section is bent or offset at the point *f*, at which place the sections are apertured for the passage of the upper member *g* of a compound hair-pin, whose lower member *h* passes through straps or stirrups *j* near the base of each section. Each offset or bent portion *f* is covered by a plate *i*, which plate is suitably secured to the said section and provides a space *k*, in which the point of the upper member *g* of the hair-pin may be sheathed, the lower member of the hair-pin being sheathed by the stirrups *j*, as will clearly appear from an inspection of Fig. 2. The apertures in the offset *f* and the covering-plate *i* are so located with respect to each other as to spread apart the ends of the hair-pin section, the stirrups *j* being likewise so located as to spread apart the ends of the hair-pin sections passing

through them. The hair-pin sections may be of any suitable or desired shape. The preferable shape is that shown in the drawings, wherein the lower section *h* comprises a looped wire of the general shape of a hair-pin and provided with bends or loops *h'*, which serve as bearings for the upper member of the hair-pin. This upper member of the hair-pin consists of a wire bent into the general shape of a hair-pin, except that the wires are crossed at the point *g'*, so as to provide stops or abutments on the hair-pin section *g* to limit the movement of the compound hair-pin, which is effected by the bent portions or abutments coming against the sides of the apertures in the sliding section of the hat-fastener, as will be well understood. The two members of the compound hair-pin are hinged together at their junction and swing independently of each other, the lower section swinging upon the line *xx*, (exhibited in Fig. 4,) so that the hair-pins will enter the hair at different degrees of inclination and firmly secure the hat to the head.

Having described my invention, what I claim, and desire to secure by Letters Patent, is—

1. In a hat-fastener, the combination of a plurality of sections each provided with means for securing it to a hat and slidably connected to each other, and a compound hair-pin sliding in each section and comprising a plurality of members joined so as to move in unison.

2. In a hat-fastener, the combination of a plurality of independent sections each provided with means for securing it to a hat and slidably connected together, and one or more compound hair-pins sliding in the sections and consisting of a plurality of members secured to each other by a pivotal connection whereby the said hair-pin sections will be moved together.

3. In a hat-fastener, the combination of a plurality of sections each provided with means for securing it to a hat and slidably connected together, a compound hair-pin sliding in each section and comprising a plurality of members or hair-pins placed one above the

other extending in the same general direction and moving in unison.

4. In a hat-fastener, the combination of a plurality of sections each provided with means for securing it to a hat and slidably connected to each other and provided with compound hair-pins comprising a plurality of hair-pins

sliding in each section and diverging from a common center or axis.

HARRY INGRAM.
